J. C. GOOSMANN

STUFFING BOX

Filed Feb. 23, 1922

INVENTOR:
Justus C. Goosmann
By Dr. J. Wilson ATTY.

UNITED STATES PATENT OFFICE.

JUSTUS C. GOOSMANN, OF CHICAGO, ILLINOIS.

STUFFING BOX.

Application filed February 23, 1922. Serial No. 538,745.

To all whom it may concern:

Be it known that I, JUSTUS C. GOOSMANN, a citizen of the United States, residing at Chicago, in the county of Cook and State of Illinois, have invented certain new and useful Improvements in Stuffing Boxes, of which the following is a specification.

This invention relates in general to stuffing boxes, and is particularly efficacious in connection with high pressure cylinders for the purpose of preventing leakage of gas or other fluid, as the case may be, around the piston rod which reciprocates through one end wall of the cylinder.

In apparatus such as reciprocating compressors for refrigerating machines for instance, it is difficult to prevent the leakage of the gaseous refrigerant around and past the reciprocating piston rod, since ordinary packings and stuffing boxes soon become sufficiently worn to permit the escape of a considerable amount of gas. I am aware that it has heretofore been proposed to overcome such leakage by maintaining a greater pressure of oil or other liquid in the stuffing box around the piston rod, but unless a very high oil pressure be maintained, the leakage will not be obviated, and if an excess oil pressure is maintained, the expense is high, and furthermore a considerable quantity of the oil will be forced around the piston rod into the cylinder upon the intake stroke of the piston.

One of the primary purposes of the present invention is to prevent leakage and loss of gas, or other fluid which may be used, in an apparatus of the character indicated, and to accomplish this result without maintaining a high oil pressure in the stuffing box and without loss of either oil or gas.

With this general aim in view, my invention contemplates a stuffing box provided with a plurality of channels or lanterns surrounding the piston in spaced relation, and mechanism connected with said channels which ensures the maintenance of a predetermined pressure in each channel, the pressures, however, being progressively stepped down in the successive channels so that the lowest pressure is maintained in that channel most remote from the cylinder. As a result there are no abrupt pressure changes in the stuffing box, but on the contrary, there exists a gradually decreasing pressure which serves to prevent leakage and loss of gas around the reciprocating piston rod.

For the purpose of facilitating an understanding of my invention, I have illustrated in the accompanying drawing a preferred embodiment thereof, and in the single view, 60 the invention is shown somewhat diagrammatically and partially in section as applied to the compressor of a refrigerating apparatus.

On the drawings, reference character 5 indicates generally the cylinder of a compressor of the double acting type, in which cylinder the piston 8 is reciprocated by means of a piston rod 9 actuated from a reciprocatory cross head 11 which in turn is driven through the connecting rod 12 from a crank 13. At its outer end the cylinder is connected with the intake pipe 14 and the delivery pipe 15, and similarly at its inner end the cylinder is connected with the intake pipe 16 and the delivery pipe 17. The two branches 14 and 16 of the intake merge into a common intake pipe 18, while the delivery branches 15 and 17 merge into the common delivery pipe 19. Suitable valves (not shown) are provided to ensure flow of gas in the proper direction through these various pipes.

The outer end of the cylinder is closed and effectively sealed by the cylinder head 21. 85 the inner end however is necessarily open to accommodate the piston rod 9, and it is for the purpose of preventing leakage around this rod that my present invention was devised.

The stuffing box proper through which the piston rod projects may be of well known or preferred construction, but the packing employed therein is so constructed and arranged as to provide a plurality, in the present instance two, of channels or lanterns 22 and 23, surrounding the piston rod and spaced apart, substantially as shown. While a greater number of these lanterns or channels may be provided in the stuffing box, I have found that for ordinary purposes two will suffice, one located near the outer end of the stuffing box and the other about intermediate the outer lantern and the end of the cylinder proper.

The gas or other fluid which escapes from the cylinder around the piston rod upon the compression stroke of the piston, enters the channel or lantern 22 from which it is conducted through a pipe 24 connected with this lantern to the casing of a controlling valve indicated generally by reference char-

acter 25. This controlling valve is of the pressure reducing type and comprises a valve seat 26 disposed within the chamber 27 with which pipe 24 communicates, and a 5 hollow valve proper 28 adapted to close against this seat and shut off, or limit as the case may be, communication between the chamber 27 and a pipe 29 connected at one end with the controlling valve beneath the 10 seat thereof and at its other end with the intake pipes leading to the compressor cylinder.

The upper end of the chamber 27 is closed by a flexible diaphragm 31 centrally perforated to receive the valve 28 to which it is securely clamped. Above the chamber 27 there is formed in the valve casing a second chamber 32, providing a similar, but larger diaphragm 33 also centrally perforated to receive 20 the valve member 28 and securely clamped thereto. Both diaphragms are clamped to seal the respective chambers at their margins. A passage 34 extending longitudinally through the valve member 28 communicates 25 through the branches 35 with the chamber 32 above the diaphragm 33. A light expansion spring 36 is interposed between the upper end of the valve mechanism, and washers 37 disposed in the upper end of the 30 chamber 38, serve to normally maintain the valve 28 in seated relation against its seat 26. The tension of this spring may be increased or diminished, if desired, by increasing or reducing the number of washers 35 37 employed.

The stuffing box lantern 23 is connected by a pipe 39 with an oil pump 41 of any preferred construction automatically actuated from the cross-head 11 through suitable mechanism including the oscillatory link 42, the 40 pump and driving mechanism being so proportioned as to supply sufficient oil for the lubrication of the piston rod and maintain the lantern full of oil which will be kept 45 under a predetermined pressure as will be later explained. The oil is delivered from the lantern 23 through pipe 43 from which it is discharged into the chamber 38 of the controlling valve from which chamber it 50 flows through the passage 34 into the pipe 29, thence through the intake branches 14 and 16 into the cylinder to lubricate the piston 8.

It will be manifest that the pressures in 55 the oil lantern 23, the valve chamber 32, and in the return pipe 29, will all be equal and that the pressure in the gas lantern 22 will be the same as that in the valve chamber 27. The diaphragms 31 and 33 are so 60 proportioned that the exposed area on the upper face of diaphragm 33 is substantially twice the area of the lower exposed face of diaphragm 31. When there is a pressure in chamber 27 equal to twice the pressure 65 in chamber 32, plus the downward pressure

exerted by the spring 36, the valve 28 will be exactly balanced, and if the pressure in chamber 27 rises, the valve will be correspondingly lifted from its seat to permit an escape of pressure from the chamber 27 into the passage 34 and pipe 29. When the pressure in chamber 27 has lowered, the valve will again be closed with the result that by this mechanism a substantially uniform pressure is maintained in the lantern 22 70 approximately twice as great as the pressure which will be maintained in the lantern 23. For the purpose of determining the amount of pressure in the lantern 22, the pipe 24 is preferably equipped with a pressure 75 gage 44.

In the operation of my invention, assuming that the machine is designed to maintain an intake pressure leading to the cylinder of twenty-two atmospheres and a compression pressure in the cylinder and the discharge pipes leading therefrom of sixty-six atmospheres, the controlling valve will maintain a pressure in the intermediate lantern 22 of forty-four atmospheres. As the piston 8 reciprocates, it will upon its compression stroke toward the left, viewing the drawing, cause some of the gas being compressed to escape around the piston rod at a pressure of sixty-six atmospheres. This escaping pressure will be opposed by a lesser pressure of forty-four atmospheres maintained in the lantern and in the pipe 24 by the controlling valve and when the pressure in this lantern and pipe rises above forty-four atmospheres, the valve 28 will be opened sufficiently to permit the escape of this pressure into the pipe 29, whence the gas is returned to the cylinder. Leakage outwardly along the piston rod from the lantern 22 is opposed by an oil pressure of twenty-two atmospheres maintained in the lantern 23, and the surplus oil delivered to this lantern, in addition to that required for piston rod lubrication purposes, is returned through pipe 43, the controlling valve and the pipe 29 to the intake pipes leading to the cylinder where the oil is employed for lubricating the piston 8. It will be apparent, therefore, that there is a gradual step-down or reduction in pressure around the piston rod, which not only obviates the employment of high oil pressure in the stuffing box and consequent leakage and oil losses resulting therefrom, but it also prevents the direct leakage and escape of gas from the cylinder and such gas as will inevitably leak into the stuffing box is also returned to the cylinder and retained within the apparatus.

It is believed that my invention and many of its inherent advantages will be understood and appreciated from the foregoing without further description, and it should be obvious that the structural details shown and described may be varied within wide 125 130

limits without departing from the essence of the invention as defined in the following claims.

I claim:

5. 1. The combination of a compression cylinder, a piston operating therein, a stuffing box surrounding the piston rod and provided with an inner and an outer annular channel surrounding said rod, means for maintaining a predetermined pressure in the inner channel, and a predetermined but lower pressure in the outer channel, and a pipe for delivering gas leakage from both channels together with lubricating oil to 15 said cylinder.
2. The combination of a compression cylinder, a piston operating therein, a stuffing box surrounding the piston rod and having a plurality of annular channels surrounding the rod, means for establishing continuous communication between the outer one of said channels and the suction side of said cylinder, means for supplying lubricant under pressure to said channel against the pressure existing in the cylinder intake, and a pressure controlling valve connected with the other of said channels and adapted when the pressure in said last mentioned channel exceeds by a predetermined amount the intake pressure of said cylinder, to establish communication between said second channel and the intake of said cylinder.
3. The combination of a compression cylinder, a piston operating therein, a stuffing box surrounding the piston rod, inner and outer channels around said rod, a pipe leading from the suction side of said cylinder, means for establishing communication between said pipe and the inner one of said channels when the pressure in said channel exceeds by a predetermined amount the pressure in said pipe, whereby a predetermined ratio of pressures between the suction side of said cylinder and said channel is maintained, means for establishing con- 45 tinuous communication between said pipe and the outer one of said channels, and means for supplying lubricant against the suction pressure of the cylinder to said last mentioned channel.
4. The combination of a compression cylinder, a piston operating therein, a stuffing box surrounding the piston rod and provided with an inner and an outer annular channel surrounding said rod, automatic means for maintaining a predetermined ratio of pressures in said channels, and a connection for returning pressure leakage along the piston rod from both of 60 said channels back to said cylinder.
5. The combination of a compression cylinder, a piston therein, a piston rod projecting from the cylinder, and a stuffing box surrounding the piston rod and provided with a plurality of annular channels, means for creating a predetermined fluid pressure in the outer one of said channels, a connection from said channel to the intake of said cylinder through which lubricating fluid and gas leaking from the cylinder along said piston rod are delivered to the cylinder, a valve interposed in said connection and provided with a pair of diaphragms of different diameters controlling the opening and closing of the valve proper, a connection between the inner one of said channels and the valve casing through which the pressure of the inner channel is exerted upon the smaller of said diaphragms, and means co-operating with the pressure from the outer channel for urging said valve against its seat to shut off communication between the inner channel and the cylinder until the pressure in 70 said inner channel exceeds by a predetermined amount the pressure in said outer channel whereupon communication between said inner channel and said cylinder is established.

JUSTUS C. GOOSMANN.
